SIFTER FOR CIGARETTE RECEPTACLES

Alfonso Gomez, San Antonio, Tex.

Application December 22, 1947, Serial No. 793,284

5 Claims. (Cl. 209—275)

1

My present invention relates to an improved sifter for cigarette receptacles and is especially adapted for use in vessels containing sand of the type conventionally used to snuff inserted cigarettes and comprising generally a screen or wire mesh strainer located in the vessel and submerged in the sand so that the accumulated cigarette butts may be extracted from the vessel without loss of sand and without the unsanitary and time-consuming manual extraction.

In the accompanying drawings I have illustrated one complete example of the physical embodiment of my invention according to the best mode I have thus far devised, but it will be understood that various changes and alterations may be made in the exemplified structure within the scope of the appended claims.

In the drawings:

Fig. 1 is a side elevational view of the device of my invention.

Fig. 2 is a vertical sectional view of the sifter at rest.

Fig. 3 is a top plan view.

Fig. 4 is a vertical sectional view of the sifter extended and ready for removal to sift the sand and remove the trash.

Referring now to the drawings wherein I have illustrated the present preferred embodiment of my invention I employ a ring frame 2 of heavy wire to which are attached by rings 4 the conventional wire mesh sphere shaped portions 6 supported on arms 8 of heavy wire and looped at 10 about the ring 2 and terminating outwardly in supporting legs 12 inturned at 14.

Secured to the straight edges 16 of the portions 6 by ring like members 1 are the sections 18 of the pyramidal inner sifter screen normally extending upwardly by rings 19 to supporting wires 22. The supporting wires 22 being hinged at an acute angle and hinged at 20 to the arms 8 supporting the portions 6. The supporting wires 22 for these sections 18 are secured by loops 24 to the disk 26 which is centrally apertured to slide upon guide rod 28, the sections 18 are secured to the disk 26 by ring members 23.

This guide rod is formed with a lower perpendicular ring portion 30, and spring 32 on the rod is confined by ring 30 below and ends 34 of legs 36 of hooks 38 secured to the ends 34 so that the disk and the sifter are normally pulled down to the position of Figs. 1 and 2.

A brace frame consists of legs 40 secured by loops 42 to ring 2 and U-supports 44 with connecting links 46 positioned above and locating the ring 30.

2

The handle 48 of the guide rod is grasped by the hand when the sifter is positioned on the upper edge 50 of a suitable vessel and the fingers will grasp and pull up the hooks 38. This movement will elevate the pyramidal sections 10 and pivot the spherical portions 6 to the position of Fig. 4 sifting the sand but carrying the trash and butts upward on the screen. The device may then be bodily removed and the trash and butts disposed of by suitable means.

Having thus fully described my invention what I claim as new and desire to secure by Letters Patent is:

1. A sifter adapted for use in cigarettes receptacles containing sand and adapted to be submerged in the sand comprising a body made of mesh screen formed from a plurality of spherical shaped portions and a plurality of pyramidal shaped portions, hinged to said first mentioned portions to form a unit, with the last portions located within said first portions and extending upwardly at an angle from the bottom edges of said first portions, and securing frame wires for the portions of the mesh screen body, an apertured disk connecting the upper edges of the pyramidal portions, a guide rod in the aperture, and manually actuated means for elevating the portions of the mesh screen body relative to the frame to sift the sand and separate trash.
2. A sifter adapted for use in cigarettes receptacles containing sand and adapted to be submerged in the sand comprising a body made of mesh screen formed from a plurality of spherical shaped portions and a plurality of pyramidal shaped portions, hinged to said first mentioned portions to form a unit, with the last portions located within said first portions and extending upwardly at an angle from the bottom edges of said first portions, and securing frame wires for the portions of the mesh screen body, an apertured disk connecting the upper edges of the pyramidal portions, a guide rod in the aperture, and manually actuated spring retracted means for elevating the portions of the mesh screen body relative to the frame to sift the sand and separate trash.
3. A sifter adapted for use in cigarettes receptacles containing sand and adapted to be submerged in the sand comprising a body made of mesh screen formed from a plurality of spherical shaped portions and a plurality of pyramidal shaped portions, hinged to said first mentioned portions to form a unit, with the last portions located within said first portions and extending upwardly at an angle from the bottom edges of

said first portions, and securing frame wires for the portions of the mesh screen body, an apertured disk connecting the upper edges of the pyramidal portions, a guide rod in the aperture, and manually actuated means on the guide rod for elevating the portions of the mesh screen body relative to the frame to sift the sand and separate trash.

4. A sifter adapted for use in cigarettes receptacles containing sand and adapted to be submerged in the sand comprising a body made of mesh screen formed from a plurality of spherical shaped portions and a plurality of pyramidal shaped portions, hinged to said first mentioned portions to form a unit, with the last portions located within said first portions and extending upwardly at an angle from the bottom edges of said first portions, and securing frame wires for the portions of the mesh screen body, an apertured disk connecting the upper edges of the pyramidal portions, a guide rod in the aperture, and manually actuated means slidable on the guide rod for elevating the portions of the mesh screen body relative to the frame to sift the sand and separate trash.

5. A sifter adapted for use in cigarettes receptacles containing sand and adapted to be submerged in the sand comprising a body made of

10
15

mesh screen formed from a plurality of spherical shaped portions and a plurality of pyramidal shaped portions, hinged to said first mentioned portions to form a unit, with the last portions located within said first portions and extending upwardly at an angle from the bottom edges of said first portions, and securing frame wires for the portions of the mesh screen body, an apertured disk connecting the upper edges of the pyramidal portions, a guide rod in the aperture, and manually actuated spring retracted means slidable on the guide rod for elevating the portions of the mesh screen body relative to the frame to sift the sand and separate trash.
